US00D868406S

(12) **United States Design Patent** (10) **Patent No.:** **US D868,406 S**
Bond et al. (45) **Date of Patent:** **** Nov. 26, 2019**

(54) **VACUUM CLEANER TOOL**

(71) Applicant: **SHARKNINJA OPERATING LLC**,
 Newton, MA (US)

(72) Inventors: **Brian M. Bond**, Woburn, MA (US);
Christopher Pinches, Surrey (GB);
Sam James, London (GB)

(73) Assignee: **SharkNinja Operating LLC**,
 Needham, MA (US)

(**) Term: **15 Years**

(21) Appl. No.: **29/611,772**

(22) Filed: **Jul. 25, 2017**

(51) LOC (12) Cl. **15-05**

(52) U.S. Cl.

(57) **CLAIM**

The ornamental design for a vacuum cleaner tool, as shown and described.

DESCRIPTION

FIG. 1 is a top perspective view of a vacuum cleaner tool, showing the new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 4 Drawing Sheets
